UNITED STATES PATENT OFFICE.

WILLIAM H. HILL AND HERBERT B. WRIGHT, OF CHICAGO, ILLINOIS.

DUMP-WAGON.

No. 877,338.

Specification of Letters Patent.

Patented Jan. 21, 1908.

Application filed October 3, 1905. Serial No. 281,146.

To all whom it may concern:

Be it known that we, WILLIAM H. HILL and HERBERT B. WRIGHT, citizens of the United States, and residents of Chicago, in 5 the county of Cook and State of Illinois, have invented certain new and useful Improvements in Dump-Wagons, of which the following is a specification.

This invention relates more particularly to 10 that type of dump wagons in which the bottom, or bottom doors, may be dropped down to dump or discharge the load; and its objects are to provide a wagon of this character which will obviate certain defects in those 15 now in use, and which will be simple and durable in construction and will not have any small parts or chains which will be apt to become broken, or to give trouble; and to provide means whereby the doors may not 20 only be dropped to dumping position, but may be raised up alongside the sides of the box to get them out of the way of the discharged material, and also means whereby either bottom door may be dropped without 25 freeing the other one.

The invention consists in the novel features of construction and arrangement of parts which will be described and claimed hereinafter and which are shown in the accompanying drawings, showing an embodiment thereof, in which:

Figure 1 is a side elevation of the dump wagon, Fig. 2 is a detail showing the bent door shaft or rod, Fig. 3 is an end view of the 35 wagon, Fig. 4 is a view showing the locking catches for the doors, Fig. 5 is an enlarged detail of said catches, and Fig. 6 is a detail showing the cranks for operating the catches.

According to our invention, the wagon 40 body 7 is preferably carried on side beams 8 which extend along the top of said body and are then bent down to rest on the axle in the rear, and bent down and in to rest on the turn-table 9 at the front. The arrangement 45 should be such that the front wheels may turn under the frame so that the wagon may be turned in a short space. The driver's seat 10 is so placed that the operating levers, to be described hereinafter, will be within 50 convenient reach. We prefer to make the wagon of all steel construction, but of course wood or other suitable material may be used in its construction.

The wagon box is provided preferably 55 with two bottom doors 11, these doors being

provided with loops or fastenings 12 which engage with rods 13 on the sides of the box to form hinges and also guide means for swinging the doors out and up alongside of the box. These rods or guides are secured at the top 60 and are bent in and up at the bottom, these upwardly bent portions being held in keepers or bearings 14 in which they are free to slide. The lower parts of the rods, or the part forming the hinge proper, may then be 65 adjusted by means of the turn-buckles 15. This will provide means whereby the bottom doors may be adjusted so that they will be tight, notwithstanding any wear which may occur to the doors or to the hinges. This is 70 an especially important feature for wagons used in hauling stone, sand or the like, such material causing rapid wear on the operating parts. The doors swing down and out as shown particularly in Fig. 3. The doors will 75 drop to the lowest dotted position shown in said figure when the holding catches are released, and may then be closed again or swung up on the outside, as shown in the highest dotted position, by means of the 80 door operating device. As these are duplicates, it will only be necessary to describe the one for one side, and for this reason, some of the parts have been omitted from the drawings for convenience in illustration. 85

A bent shaft 16, shown in Fig. 2, extends the full length of the door and has its bearing 17, on the door, and end bearings 18 on the box. This shaft is provided at the front end with a lever 19 by means of which it may be 90 turned in one direction to close the door, after it has been opened, or may be swung in the opposite direction to bring the door up to the side of the box, in order that the wagon will clear the load just dumped, whether it is 95 driven ahead, or turned shortly to one side. This is a feature which we believe will add greatly to the convenience in operating the wagon, and one which has not heretofore been put into use. By means of this construction, we also do away with the chains which have been used for such purpose and which give a great amount of trouble.

The door may be held in any position by the ratchet 33 and pawl 34. The door is 100 held in closed position by means of catches or hooks 20, one at each end of the box for each door. These catches are secured to and operated by springs 21 which extend up and over the top of the box in order to give them 110

a good bearing as they support the load. These springs press the catches normally in to engage the door, and the tension on such springs may be adjusted by the rod 22 which 5 passes through holes in the brackets 23, these holes being arranged at different heights and at different distances from the box.

The catches are operated by means of crank rods 24, such rods having their bearings in boxes 25 and 26 on the ends of the 10 wagon body; the former being made integrally with the bearings 18, and the latter serving to hold the two adjacent ends of the rods at one end of the body. These rods are 15 preferably made separate so that either door may be dropped as desired but one rod might be made to operate both catches at one end if desired. The front end rod is operated by means of a lever 27, and in order to throw the 20 catch on the rack end simultaneously, this lever is connected by means of a rod 28 to a crank lever 29 on the end of the back rod as shown in Fig. 1, the lever being shown in this position in full lines as though the catches 25 were thrown out. The crank part of the rod 24 passes through an opening in the catch 20 as shown in Fig. 5, the arrangement being such that, as the lever 27 is thrown rearward and held by the spring lock 30, the catch is 30 locked as shown in the full lines. Then as the lever is released from the lock and swung out a short distance, the crank part will come into the larger opening and will allow the catches to swing freely either out, or in to 35 engage the door. A still further movement of the lever 27 will cause the crank to engage the catch and throw it out as shown in dotted lines. In order to reduce the wear and friction when the catch is being thrown out to 40 release the bottom, we provide the bearing box 31 with the roller 32 therein in the engaging edge of the bottom door as shown in Fig. 5.

Having thus described our invention, 45 what we claim and desire to secure by Letters Patent is.

1. The combination of a wagon box, a bottom door for said box, hinge members on said door, vertically adjustable rods on said 50 box adapted to engage with said hinge members, and means for adjusting said rods.

2. The combination of a wagon box, doors for the bottom of said box, loops on said doors, and adjustable rods along the sides of 55 said box with which said loops engage, the

arrangement being such that the doors can be raised up alongside said box.

3. The combination with a wagon box, of adjustable rods on the side of said box, and a bottom door having bearings engaging 60 with said rods.

4. In a device of the character set forth the combination with a wagon box of a swinging door hinged to the said box with 65 slideable hinges and a bent shaft arranged lengthwise of said door, said shaft having bearings on the wagon box and also bearings on said door, the arrangement being such that the door may be operated by means of said shaft, said slideable hinge providing for 70 a lateral movement of the door.

5. A wagon box provided with a bottom door, a bent shaft arranged longitudinally of said box, bearings on said box for engagement with the ends of said shaft, bearings on 75 said door for engagement with the offset portion of said shaft, and means for swinging said shaft for operating said door.

6. The combination of a wagon body, bottom doors for said body adapted to swing 80 down, a bent shaft engaging with bearings on said door and having bearings on said body, and a lever for swinging said shaft to operate the door either to close the same or to swing it up along the side of the body. 85

7. In combination, a wagon body, a longitudinal door pivotally attached to said body, cranks pivoted adjacent to the outer lower corners of the ends of said body, a shaft connecting the outer ends of said 90 cranks and extending longitudinally of said door and engaging therewith, and means for turning said cranks to close said door or to swing said door down and up alongside the sides of said body. 95

8. The combination of a door-catch, a bent rod having a crank portion engaging with said catch, the opening through said catch for the rod being so shaped that when the rod is in one position the catch will be 100 locked to hold the door, when the rod is swung to the next position the catch will be free to move, and when the rod is swung still further the catch will be thrown out of engaging position. 105
